TOY GUN

Hiroshi Yano, 2 1-chome, Jinai-cho, Moriguchi-shi,
Osaka, Japan

Filed Nov. 16, 1964, Ser. No. 82,602

Term of patent 14 years

(Cl. D34—15)

FIG. 2.

FIG. 4.

FIG. 1.

FIG. 5.

FIG. 3.

FIGURE 1 is a side elevational view of a toy gun showing my new design, the opposite side being substantially the same;

I claim:

The ornamental design for a toy gun, as shown and described.
